MECHANISM FOR OPENING AND CLOSING
HINGED WINDOWS AND THE LIKE

Jack Fox-Williams, London, England

Application September 7, 1937, Serial No. 162,816
In Great Britain September 16, 1936

8 Claims. (Cl. 268—119)

This invention relates to mechanism for opening and closing hinged windows, shutters and like hinged members (hereinafter referred to for the sake of convenience as windows) of the kind in which one end of a bar acts on the window while the other end is acted upon by suitable operating mechanism arranged to move the bar so as to open and close the window.

The invention is particularly but not exclusively intended to be applied to windows for use, for example, in tropical countries where a fixed insect screen is provided on the inside of the window to exclude insects when the window is open.

In such windows it has previously been proposed to secure to the under side of the lower horizontal member of the frame supporting the glass, hereinafter referred to as the window frame, a guide of channel section in which is arranged to slide a metal plate which is connected by a pivot to the adjacent end of the bar while the other end of the bar is pivoted to the window sill or other fixed part and is formed with or rigidly secured to a toothed quadrant engaged by a worm adapted to be rotated by a handle so that rotation of the handle causes the bar to swing about its pivot to open or close the window, the plate sliding in the channel section member.

With such an arrangement it is necessary to leave between the lower horizontal member of the window frame and the corresponding member of the surrounding frame a space sufficient to accommodate the channel section member, the bar and the pivot connecting the bar to the sliding plate, and it is an object of the present invention to provide improved operating mechanism for windows and other hinged members which, when applied to windows, will allow of a smaller clearance being left between the lower horizontal member of the window frame and the corresponding member of the surrounding frame than was possible with the previous arrangement referred to above.

To this end according to the present invention mechanism of the kind referred to for opening and closing hinged windows, shutters and like hinged members comprises an operating bar one end of which is adapted to be pivotally connected to the lower peripheral face of the upper or lower horizontal member of the window frame so as to lie at least partly in the space between this member and the corresponding member of the surrounding frame and operating mechanism acting on the other end of the bar and adapted not only to apply an endwise force to the bar when

the position of the window is such that movement of the bar to open or close it will be mainly in the endwise direction, but also to apply a force tending to cause the bar to swing outwards or inwards when the position of the window is such that movement of the bar to open or close the window will be mainly a swinging movement, that is to say during that part of the opening or closing movement of the window when the longitudinal axis of the bar passes through or close to the axis of the window hinges.

Thus, when the window is in such a position that a purely endwise force applied to the bar would not readily move the window about its hinges, the operating mechanism will apply a force tending to cause the bar to swing outwards or inwards for this purpose while at other times movement of the window will be caused mainly by an endwise force applied to the bar by the operating mechanism.

The operating mechanism may be constructed and arranged in various ways. In one arrangement, however, there is formed or rigidly mounted on the end of the bar remote from that pivoted to the window a toothed rack engaged by a pinion or worm adapted to be rotated by hand-operated mechanism, and means, for example pin and slot mechanism, which controls the movement of this end of the bar in such a manner as to maintain the toothed rack always in engagement with the pinion or worm while permitting the required endwise and swinging movements of the bar. Thus, the pinion acts through the rack to apply to the bar a force which, during part of its movement, tends to cause what is mainly a swinging movement about a point adjacent to the pinion and during the other part of its movement is mainly an endwise movement of the bar.

Thus, in one such arrangement where the pivotal axis of the window lies on the side of the plane thereof towards which the window opens, the toothed rack would be formed so that on initial rotation of the gear wheel or worm to open the window a force is applied to the bar to move it endwise in one direction and also to cause it to swing outwards about a point adjacent to the pinion while thereafter the force will tend to move the bar endwise in the opposite direction, that is after the longitudinal axis of the bar has passed through the axis of the window hinges.

A construction of the above type according to the invention is illustrated by way of example in the accompanying drawings, in which

construction showing the parts in the "closed" position,

Figure 2 is a similar view to Figure 1 showing the parts in a "partly open" position,

Figure 3 is a section on the line 3—3 of Figure 1 on an enlarged scale, and

Figure 4 is a front elevation of the construction shown in Figures 1-3.

In the construction illustrated, the frame A of the window is carried on arms B hinged at B¹ at a point outside the plane of the window.

Pivoted at A¹ to the underside of the bottom member A² of the window frame is one end of a bar C which extends through a slot in the part D¹ of the bottom member D of the surrounding frame, that is the frame in which the window frame is mounted, into a casing E secured to the inner face of the member D. The inner end portion of the bar C is formed as a sinuous rack as shown at C¹ and its inner end carries a roller C² mounted on a pin and sliding in a channel or guide E¹ fixed to the casing E.

The rack C¹ engages a pinion F mounted in bearings in the casing E and meshing with a second pinion F¹ rigidly secured to a spindle F² also mounted in bearings in the casing. The spindle F² also has rigidly secured to it a worm wheel F³ engaged by a worm G on a spindle G¹ extending through the casing E and provided at its outer end with an operating handle G².

It will be seen that by rotating the handle G² the pinions F and F¹ can be caused to rotate so that the pinion F acts on the rack C¹. During the initial movement from the position shown in Figure 1 the rack C¹ and hence the bar C will be caused to move to the right and also swing outwards about the roller C² so as to effect the initial opening of the window, say, into the position shown in Figure 2, the movement to the right being necessary in view of the position of the hinge B¹ while the outward swinging movement applies the necessary force to the window to move it in spite of the fact that the hinge B¹, pivot A¹ and roller C² are during this time nearly in line.

During operation to cause opening movement of the window beyond the position shown in Figure 2, the movement of the rack C¹ and bar C is mainly endwise and it will be seen that at this time an endwise force is all that is necessary to move the window. On rotation of the handle G¹ to close the window, the opposite operation occurs, and it will thus be seen that the force applied to the rack C¹ and bar C and by it to the window will always be in the direction necessary to move the window, whatever its position may be.

Further, the construction permits of the mounting of an insect screen on the inside of the frame D and the opening and closing of the window without interfering with this screen.

It will be understood that the worm and wormwheel are preferably made so as to provide an irreversible drive, making it impossible for the window to be moved by a force applied to it for example by the wind and that the gear ratio of the worm and wormwheel or of the gear wheels F and F¹ or both may be varied to suit requirements.

It will also be seen that with the present invention it is only necessary to leave sufficient room between the bottom member A² of the window frame and the corresponding member D of the surrounding frame to accommodate the arm C since the head of the pivot A¹ can be countersunk. By making the arm C, as would be usual,

in the form of a strip of small thickness therefore, the space which must be left between the members A² and D can be materially reduced as compared with the previous arrangement referred to in the opening part of the present specification.

It is to be understood that the invention has been described with particular reference to the lower horizontal member of a window for the sake of convenience only and that the invention is equally applicable to the upper horizontal member of a window or to either one of the two edges of a window, shutter or like hinged member which lie in planes at right angles to the axis of the hinge or hinges whether this axis is vertical, horizontal or inclined.

Further, the construction more particularly described above with reference to the drawings is given by way of example only and other constructions may be adopted within the scope of the appended claims without departing from this invention.

What I claim as my invention and desire to secure by Letters Patent is:—

1. Operating mechanism for hinged windows, shutters and like hinged members the pivotal axis of which lies on the side of the plane thereof towards which the window, shutter or like hinged member opens, including in combination an operating bar one end of which is adapted to be pivotally connected to the window and operating mechanism acting on the other end of the bar comprising a rack rigid with the bar and having a main longitudinally extending part terminating at the end adjacent to the pivot connecting the bar to the window in a curved part extending through an angle of more than 90°, a pinion engaging the rack, means controlling the movement of the rack to maintain it always in engagement with the pinion, and means for rotating the pinion whereby during the initial opening movement, the bar is caused to move in the direction of its length in one direction and also to swing to the required extent whereas for subsequent opening movement of the window the bar is caused to move in the direction of its length in the opposite direction.

2. Operating mechanism for hinged windows, shutters and like hinged members the pivotal axis of which lies on the side of the plane thereof towards which the window, shutter or like hinged member opens, including in combination an operating bar one end of which is adapted to be pivotally connected to the window and operating mechanism acting on the other end of the bar comprising a rack rigid with the bar and having a main longitudinally extending part terminating at the end adjacent to the pivot connecting the bar to the window in a curved part extending through more than 90°, a pinion engaging the rack, pin and slot mechanism controlling the movement of the rack to maintain it always in engagement with the pinion, and means for rotating the pinion whereby during the initial opening movement, the bar is moved in the direction of its length in one direction and also caused to swing to the required extent whereas for subsequent opening movement of the window the bar is caused to move in the direction of its length in the opposite direction.

3. Operating mechanism for hinged windows, shutters and like hinged members the pivotal axis of which lies on the side of the plane thereof towards which the window, shutter or like hinged member opens, including in combination an oper-

ating bar one end of which is adapted to be pivotally connected to the window, and operating mechanism acting on the other end of the bar comprising a rack rigid with the bar and having a main longitudinally extending part terminating at the end adjacent to the pivot connecting the bar to the window in a curved part extending through an angle of more than 90°, a pinion engaging the rack, means controlling the movement of the rack to maintain it always in engagement with the pinion, and worm and worm-wheel mechanism for rotating the pinion whereby during the initial opening movement, the bar is moved in the direction of its length in one direction and also caused to swing to the required extent whereas for subsequent opening movement of the window the bar is caused to move in the direction of its length in the opposite direction.

4. Operating mechanism for hinged windows, shutters and like hinged members the pivotal axis of which lies on the side of the plane thereof towards which the window, shutter or like hinged member opens, including in combination an operating bar one end of which is adapted to be pivotally connected to the window, and operating mechanism acting on the other end of the bar comprising a rack rigid with the bar and having a main longitudinally extending part terminating at the end adjacent to the pivot connecting the bar to the window in a curved part extending through an angle of more than 90°, a pinion engaging the rack, pin and slot mechanism controlling the movement of the rack to maintain it always in engagement with the pinion, and worm and wormwheel mechanism for rotating the pinion, whereby on rotation of the pinion to cause the initial opening movement, the bar is moved in the direction of its length in one direction and also caused to swing to the required extent whereas for subsequent opening movement of the window the bar is caused to move in the direction of its length in the opposite direction.

5. Operating mechanism for hinged windows, shutters and like hinged members including in combination an operating bar one end of which is adapted to be pivotally connected to the window and operating mechanism acting on the other end of the bar comprising a rack rigid with the bar and having a main longitudinally extending part terminating at the end adjacent to the pivot connecting the bar to the window in a curved part, a pinion engaging the rack, means controlling the movement of the rack to maintain it always in engagement with the pinion and means for rotating the pinion whereby during the initial opening movement when the pinion is acting on the curved part of the rack the bar is caused to execute a movement which is mainly a swinging movement whereas for subsequent opening movement of the window when the pinion is engaging the longitudinally extending part of the rack, the movement of the bar is mainly in the direction of its length.

6. Operating mechanism for hinged windows,

shutters and like hinged members including in combination an operating bar one end of which is adapted to be pivotally connected to the window and operating mechanism acting on the other end of the bar comprising a rack rigid with the bar and having a main longitudinally extending part terminating at the end adjacent to the pivot connecting the bar to the window in a curved part, a pinion engaging the rack, pin and slot mechanism controlling the movement of the rack to maintain it always in engagement with the pinion, and means for rotating the pinion whereby during the initial opening movement when the pinion is acting on the curved part of the rack the bar is caused to execute a movement which is mainly a swinging movement whereas for subsequent opening movement of the window when the pinion is engaging the longitudinally extending part of the rack, the movement of the bar is mainly in the direction of its length.

7. Operating mechanism for hinged windows, shutters and like hinged members including in combination an operating bar one end of which is adapted to be pivotally connected to the window and operating mechanism acting on the other end of the bar comprising a rack rigid with the bar and having a main longitudinally extending part terminating at the end adjacent to the pivot connecting the bar to the window in a curved part, a pinion engaging the rack, means controlling the movement of the rack to maintain it always in engagement with the pinion and worm and worm wheel mechanism for rotating the pinion whereby during the initial opening movement when the pinion is acting on the curved part of the rack the bar is caused to execute a movement which is mainly a swinging movement whereas for subsequent opening movement of the window when the pinion is engaging the longitudinally extending part of the rack, the movement of the bar is mainly in the direction of its length.

8. Operating mechanism for hinged windows, shutters and like hinged members including in combination an operating bar one end of which is adapted to be pivotally connected to the window and operating mechanism acting on the other end of the bar comprising a rack rigid with the bar and having a main longitudinally extending part terminating at the end adjacent to the pivot connecting the bar to the window in a curved part, a pinion engaging the rack, pin and slot mechanism controlling the movement of the rack to maintain it always in engagement with the pinion and worm and worm wheel mechanism for rotating the pinion whereby during the initial opening movement when the pinion is acting on the curved part of the rack the bar is caused to execute a movement which is mainly a swinging movement whereas for subsequent opening movement of the window when the pinion is engaging the longitudinally extending part of the rack, the movement of the bar is mainly in the direction of its length.

JACK FOX-WILLIAMS.
